US00D584248S

(12) **United States Design Patent**
Sung et al.

(10) **Patent No.:** US D584,248 S
(45) **Date of Patent:** ** Jan. 6, 2009

(54) **LIGHT EMITTING DIODE**

(75) Inventors: **Jae-Hoon Sung**, Seoul (KR); **Kham Lee**, Goyang-si (KR)

(73) Assignee: **Alti-Electronics, Co., Ltd.**, Yongin-Si (KR)

(**) Term: **14 Years**

(21) Appl. No.: **29/290,979**

(22) Filed: **Feb. 5, 2008**

(30) **Foreign Application Priority Data**

Aug. 20, 2007 (KR) 30-2007-0035379

(51) **LOC (9) Cl.** 13-03

(52) **U.S. Cl.** D13/180

(58) **Field of Classification Search** D13/180; D26/2; 257/79, 80, 81, 88, 89, 95, 98, 99, 257/100; 313/483, 498, 500; 362/555, 800

See application file for complete search history.

(57) **CLAIM**

The ornamental design for a light emitting diode, as shown and described herein.

DESCRIPTION

FIG. 1 is a perspective view of a light emitting diode showing our new design;

FIG. 2 is a front elevational view thereof;

FIG. 3 is a rear elevational view thereof;

FIG. 4 is a left side elevational view thereof and the right side elevational view is a mirror image of the left side elevational view;

FIG. 5 is a top plan view thereof; and,

FIG. 6 is a bottom plan view.
